UNITED STATES PATENT OFFICE.

JOHN D. FISKE, OF BALTIMORE, MARYLAND.

APPARATUS FOR LOADING OR UNLOADING VESSELS.

SPECIFICATION forming part of Letters Patent No. 408,702, dated August 13, 1889.

Application filed November 23, 1888. Serial No. 291,639. (No model.)

To all whom it may concern:

Be it known that I, JOHN D. FISKE, a citizen of the United States, residing at Baltimore, in the State of Maryland, have invented 5 certain new and useful Improvements in Apparatus for Loading or Unloading Vessels, of which the following is a specification.

This invention relates to an improved apparatus for loading or unloading vessels, 10 and will first be described, and then set forth in the claims.

The invention is shown in the drawings herewith, in which—

Figure 1 is a top view of a vessel having 15 my improved apparatus. Fig. 2 is a side view of same, showing the vessel partly in section. Fig. 3 is an elevation showing a cross-section of the vessel and wharf. Fig. 4 shows the parts comprising the apparatus unconnected 20 with the vessel. Figs. 5 and 6 illustrate in detail the form of clutch shown in Figs. 1 to 4. Figs. 7 and 8 illustrate a modification in the construction of the clutch. Fig. 9 illustrates some modifications of the apparatus un- 25 connected with the vessel. Figs. 10 and 11 are detail views of the modified construction of clutch shown in Fig. 9.

In the present instance where a vessel is shown in the illustrations the apparatus is ar- 30 ranged for unloading the cargo of the vessel.

Referring to the drawings, the letter A designates a vessel; a, the deck-hole; B, the mast; C, a gaff projecting from the upper part of the mast over the deck-hole a, and D a boom 35 projecting from the mast to the wharf E.

All of the parts just mentioned are of ordinary construction, and are well known.

My improvements are contrived with a view 40 to using but one winch where two have usually heretofore been required.

Attached to the bucket F is a hoist-rope b, which is wound upon a winch G. Three pulley-blocks are employed in connection with the hoist-rope b. These blocks are arranged 45 as follows: The first one c' is attached to the gaff C, the second one c² to the boom D at a point a little beyond where it is desired the bucket shall be dumped, and the third one c³ to the gaff C. The hoist-rope passes from the 50 winch G up and over the first pulley-block c', thence down to the second block c², forming a carrier-stretch b', thence up to the third

block c³, and from there to the bucket F, the latter forming a lift-stretch b². This arrangement of three pulleys, one rope, and one 55 winch enables the one rope to serve for hoisting the bucket vertically and then for carrying it laterally. To produce this result, however, a suitable clutch-device H must be employed to coact with the two stretches of the rope, 60 which I term the "carrier-stretch" b' and the "lift-stretch" b². This clutch H may be constructed in various ways, and two forms are illustrated, one in Figs. 5 and 6 and the other in Figs. 7 and 8; but my present invention is 65 not limited to any particular construction of clutch.

The body of the clutch has at one end a slot d, and a friction-roller e is mounted in this slot. The lift-stretch b² of the rope passes freely 70 through this slot, as shown. At the other end of the clutch-body is another slot f, which is occupied by clutch-plates g, which are pivoted. The carrier-stretch b' of the rope passes between these clutch-plates g, which may be 75 more separated to allow the rope to pass freely or may be brought closer together to clutch or take hold of the rope. A cord h is attached to the clutch H and serves to actuate it or cause its plates g to take hold of the 80 said carrier-stretch b'. The cord h passes from the clutch to an eye or pulley i on the gaff C, thence to another eye or pulley i' on the mast B, and thence down along the mast to the deck of the vessel. This cord h has an 85 attached ring or loop k, and a pin or hook l on the mast or other convenient place of support serves for the engagement of said ring.

In unloading a vessel the apparatus will operate in the following-described manner: 90 Assuming the bucket F to be down the deck-hole a and ready to be hoisted out, that end of the clutch H to which the plates g are attached must be lifted and supported by the cord h. This may be done by the person in 95 charge of the winch, who will pull the cord h and engage its ring k with the said hook l. Thereby the position of the clutch-body H with respect to the carrier-stretch b' will be that indicated by broken lines in Fig. 5. 100 When the plate end of the clutch-body is thus lifted, it will have the effect to more widely separate the two pivoted clutch-plates g, and the rope may then pass between them freely.

The winch G should then be started to wind up on the rope and hoist the bucket F vertically. Upon the bucket reaching a sufficient height the winch will be stopped and the ring 5 *k* of the cord must then be disengaged from the hook *l*. Thereupon the plate end of the clutch will lower by the action of gravity and its position will be that shown in full lines in Fig. 5, and the clutch-plates *g* will thereby be 10 brought closer together and take hold of the carrier-stretch *b'*. The winch should then be started to unwind, the effect of which will be to laterally carry the bucket F from its position directly over the deck-hole *a* toward the 15 pulley *c'* on the boom. When the bucket is over the wharf, it may be dumped. By again winding upon the winch the empty bucket will move laterally in the reverse direction until again over the deck-hole, when the cord 20 *h* will be pulled to lift the plate end of the clutch *H* and loosen its hold on the carrier-stretch *b'*. Then the winch may be reversed to allow the bucket to lower into the deck-hole.

As already stated, the clutch to take hold 25 of the carrier-stretch *b'* may be constructed in various ways, and as an example of the modifications that are practicable reference is made to Figs. 7 and 8. This clutch-body *H* has the slot *d* and roller *e* at one end and 30 a slot *f* occupied by clutch-plates *g* at the other end; but in this case the two clutch-plates *g* are pivoted to a jointed section *II'* of the clutch-body. The two parts of the body *H* *H'* are connected by a joint *m*. A spiral 35 spring *n* is placed between the two parts, and serves to keep them normally spread apart, as in Fig. 7. The ends of the spring rest in recessed seats *n'*. When the two parts *H* *H'* are spread, as stated above, the effect on the 40 two clutch-plates *g* is to bring them closer together and cause them to take hold of the rope. A cord *h* is attached to the free end of the body-section *II'*, and passes through a suitable hole *o* in the other body-section *H*, 45 and thence this cord should pass to the eye or pulley *i* on the gaff *C*, as in Fig. 4. When the cord *h* is pulled, the effect will be to bring the jointed parts *H* *H'* of the clutch-body close together, and also lift the end of the 50 clutch to which the plates *g* are attached, the effect of which will be to more widely separate the said two clutch-plates *g* and allow the rope to pass between them freely.

Fig. 9 shows a somewhat different organization of the apparatus and combines three pulleys, one winch, rope arranged to form a carrier-stretch and lift-stretch, a clutch co-acting with the said two stretches of rope, and a cord to actuate said clutch. In this case the

hoist-rope *b* passes from the winch *G* up and 60 over the first pulley-block *c'*, and then down to the bucket *F*, this down part forming the lift-stretch *b'*. The so-called "carrier-stretch" *b'* in this case consists of an endless rope over the second and third pulley-blocks *c'* and *c'*. 65 The clutch *II'* has one end secured fast to the carrier-stretch *b'*, and the other end has a slot *p* and two clutch-hooks *q* pivoted in the slot. The lift-stretch *b'* of rope passes freely through the slot and between the said two 70 hooks *q*. This lift-stretch is provided with a taper or cone-shaped swell *r*, which, when the bucket is being hoisted, may pass up between the hooks *q*, and then the hooks will close below it, whereupon the winch may be 75 reversed, the effect of which will be to laterally carry the bucket *F* toward the pulley *c'*, where it may be dumped. After dumping, the bucket may be brought to a position over the deck-hole by winding up on the winch, 80 when the cord *h* may be pulled to separate the clutch-hooks *q* and loosen their hold on the said swell *r*. Then the winch may be reversed to unwind and lower the bucket into 85 the vessel.

Having described my invention, I claim—

1. The combination of three pulleys, two of which *c'* *c'* are near together and the other *c'* at a lateral point therefrom, one winch, rope arranged over said pulleys to form a 90 lateral carrier-stretch *b'*, and a lift-stretch *b'*, a clutch coacting with said two stretches of rope, and a cord *h*, attached to the clutch for actuating it, as set forth.

2. The combination of three pulleys, two of which *c'* *c'* are near together, and the other *c'* at a lateral point therefrom, one winch, a rope passing from the winch to the first pulley *c'*, then laterally to the second pulley *c'*, thereby forming a carrier-stretch *b'*, thence to the 100 third pulley *c'*, and then down to form a lift-stretch *b'*, and a clutch coacting with said carrier-stretch and lift-stretch, for the purpose set forth.

3. The combination of a rope lift-stretch *b'*, 105 a carrier-stretch, both of said stretches passing over pulleys, a rope-clutch having a body provided with a slot through which the lift-stretch passes freely, and having two pivoted clutch-plates *g*, between which the carrier-stretch *b'* passes, and a cord *h*, attached to the 110 said clutch for actuating it, as set forth.

In testimony whereof I affix my signature in presence of two witnesses.

JOHN D. FISKE.
